UNITED STATES PATENT OFFICE

JOHN R. ROBERTSON, OF SYRACUSE, NEW YORK.

DESIGN FOR PLANT-STAND.

Specification forming part of Design No. 6,580, dated April 8, 1873; application filed January 23, 1873.

To all whom it may concern:

Be it known that I, JOHN R. ROBERTSON, of Syracuse, county of Onondaga and State of New York, have invented certain new and useful Improvements in Design for Plant-Stands, of which the following is a specification:

The nature of my invention relates to the construction of an ornamental plant-stand; and consists in a wooden standard, which is provided with shoulders, upon which rest the supporting-rings. To these rings are secured sockets, in which the plates for holding the flower-pots are pivoted.

The accompanying photographic illustration represents my invention.

a represents a tapering wooden standard, which fits in a tapering socket in the iron feet. b. Upon the sides of this standard are formed four (more or less) shoulders, over which the collars c are passed. Formed with the two lower rings are a number of sockets, d, in which are pivoted the ornamental shelves e, each one of which can be partly swung around, and which are intended to receive a flower-pot. By turning the collar around the shelves can be changed from side to side, as may be desired. To the upper collars are cast round flat plates i, which have an ornamental border around their edges.

The whole stand forms an elegant and ornamental plant-stand for rooms and parlors, and greatly adds to the beauty of the flowers.

Having thus described my invention, what I claim as new, and desire to secure by Letters Patent, is—

The standard a, foot b, and shelves e and i, substantially as described.

In testimony that I claim the foregoing as my invention I hereunto affix my signature this 16th day of January, 1873.

JOHN R. ROBERTSON.
